METHOD OF MAKING GARMENT CLOSURES

Louis Markin, Chicago, Ill., assignor to Alfred Decker & Cohn, Inc., Chicago, Ill., a corporation of Illinois

Application October 20, 1937, Serial No. 170,095

4 Claims. (Cl. 2—234)

This invention relates to the fastening of so-called zippers to garment opening closures.

Generally stated, the object of the invention is to provide a novel and improved method or process for the fastening of the two zipper sections to the garment, in a manner that will not only reduce the cost of production, in the manufacture of the garments having zipper closures of this character, but which will insure a better and neater piece of work, and a better appearance for the garment.

To the foregoing and other useful ends, the invention consists in matters hereinafter set forth and claimed and shown in the accompanying drawing in which—

Fig. 1 is a plan view of the two zipper sections connected together by the usual slide.

Fig. 2 is a similar view showing the two sections separated, and the said slide disconnected therefrom.

Fig. 3 is a plan view of the outer fly strip of a garment, such as a pair of trousers, showing one section of the zipper fastened by stitching thereto.

Fig. 4 is a similar plan view of the inner fly strip, having the other section of the zipper fastened thereto.

Fig. 5 is an inside view showing the outer fly strip secured to the garment.

Fig. 6 is an inside view showing the inner fly strip secured to the garment.

Fig. 7 is a fragmentary inside view of the garment, showing the two zipper strips joined together by the slide.

Fig. 8 is an outside view of the garment, showing the outer fly turned back a distance, and showing the metal stop piece inserted at the lower end of the zipper.

Fig. 9 is an enlarged perspective view of the 40 staple that forms the stop at the lower end of the zipper.

Fig. 10 is a detail horizontal section of said stop, and the parts to which it is attached, on line 10—10 in Fig. 8 of the drawing.

As thus illustrated, the method of applying the two zipper sections 1 and 2 shown in Fig. 1, to the garment, involves the preliminary separation of these two strips, and their disengagement from the slide 3, or their use separately, before they 50 have ever been connected together, as shown in Fig. 2 of the drawing. It will be understood, of course, that these zipper sections each consist of a row of metal engaging portions fastened to a strip of tape, and that it is the latter which is thereafter stitched or sewed to the garment.

These so-called zipper fasteners are common and well known, and are supplied in quantities to the manufacturers of clothing and other articles. Ordinarily, the two zipper sections are sold locked together by the said slide, but for the purpose of this new method the two zipper sections come to the clothing manufacturer in a separated condition, say in a bag, and with the slides requisite for the total number of pairs of sections in another bag.

Thereafter, one zipper section is sewed or stitched to the inside of the outer fly strip 4, which latter is usually made of cloth of any suitable or desired character. This step also includes the fastening of the other zipper section to the inner fly-strip 5, which latter may be of any suitable material.

Thereafter, the two fly strips 4 and 5 are fastened to the closure of the opening of the garment, as shown in Figs. 5 and 6.

After that, the said slide 3 is then applied to the two zipper sections, as shown in Fig. 7 of the drawing, which shows the inside of the garment.

Finally, with the two zipper sections and the two fly strips suitably stitched or sewed to the garment, and with the said slide 3 thereafter placed in position to operate the zipper sections, to either open or close the garment opening, the metal stop piece 6 is then inserted to join the lower ends of the two rows of metal engaging elements of the two zipper sections, so that the garment, such as a pair of trousers, is thereby provided with a finished zipper opening for the garment, as shown in Fig. 8 of the drawing, which shows the outside of the garment with a portion of the outer fly turned out and back to show the two converging rows of zipper engaging elements. The said metal stop pieces 6, one for each pair of zipper sections, may be delivered to the manufacturer in a separate bag.

By thus having the zipper sections delivered to the clothing manufacturer in separated condition, the work of applying the zipper to the garment is very greatly facilitated, for the manufacturer is relieved of the necessity of separating the members of each pair of sections, as the latter come to the manufacturer separately and ready for separate attachment to the garment.

This method of securing the zipper sections to the garment, by first securing each section to one of the flies of the so-called fly opening of the garment, and thereafter securing the fly strips to the garment, tends to reduce the cost of production in the manufacture of garments of this kind, as it reduces the time and work necessary to attach

the zippers to the garments. In addition, the work is done more smoothly, and in a much neater manner, so that the garment sets smoother and has a better appearance. Thus it is found that a 5 more satisfactory garment is provided, and that in addition a considerable saving is effected in the cost of manufacture, as compared with the production of garments by the previous methods of attaching the so-called zipper fasteners thereto.

10 It will be seen, therefore, that the connecting staple or stop means 6 is not inserted until after the slide 3 has been applied to the two zipper sections, the latter not being interconnected until after their respective fly sections are secured to 15 the garment. As shown in Figs. 5 and 6 and 7, the slide 3 can be applied to the lower ends of the two zipper sections and moved upwardly a distance so that the staple or metal fastener 6 can thereafter be applied to prevent separation of the 20 zipper sections at their lower ends. It is an important consideration, therefore, that the two zipper sections are not connected together by the slide 3 until after they are secured to the garment, and that this slide is applied to the two zipper 25 sections before the staple or metal fastener 6 is applied to permanently connect together the lower ends of the two zipper sections. Thus the entire garment can be made, practically complete, with the exception of the slide 3 and the staple 6, and 30 the slide can then be applied, and thereafter the staple can be inserted, so that the insertion of the metal staple or fastener 6 may be, if desired, the final step in the finishing of the garment. At least, it may be the final step in the application 35 of the zipper to the garment, and in any event it constitutes the first time that the lower ends of the two sections have ever been fastened together by a staple or equivalent means, after the two sections and their respective fly strips have been 40 separately sewed to the garment. Obviously, if the lower ends of the tapes 1 and 2 are stapled or otherwise fastened together, when they come to the manufacturer of the trousers, then they must first be broken apart at their lower ends before 45 they can be used in the process shown and described. And that is what is avoided by the invention shown and described and claimed. This saves time and work and reduces the cost of production.

Thus it will be seen that, according to Figs. 7 and 8 of the drawing, the slide 3 and the staple or metal stop 6 are applied to the lower end portions of the zipper sections, and that this is all done after the upper end portions of the zipper sections are fastened in place on the garment. 5

What I claim as my invention is:

1. The method of applying a zipper fastener to a garment having an opening closure therefor, comprising the providing of the two zipper sections disconnected from each other, fastening one section to the inner fly strip of said opening, and the other zipper section to the outer fly strip of said opening, thereafter incorporating or fastening the two fly strips in the garment, with the two zipper sections still unconnected to each other, thereafter providing slide means connection between the engaging portions of the two zipper sections, while the latter are still unconnected at their lower end, and after the two fly strips have 20 been sewed in place, so that the two zipper sections are not connected together until after the two fly strips and their respective zipper sections have been fastened in the garment, and thereafter for the first time joining the lower ends of 25 the two rows of engaging portions.

2. A method as specified in claim 1, comprising the insertion of a metal stop to join together the adjacent lower ends of the two rows of metal engaging portions of the two zipper sections, 30 after the application of the slide means to the two sections, and after the unconnected upper ends of the two sections have been fastened in place on the garment.

3. A method as specified in claim 1, comprising 35 the suitable joining together of the adjacent lower ends of the two rows of metal engaging portions of the two zipper sections, after the application to the latter of the slide means, and after the unconnected upper ends of the two sections have 40 been fastened in place on the garment.

4. A method as specified in claim 1, said slide means being inserted on the lower ends of the two zipper sections, and moved upwardly, and the two lower ends of the zipper sections being 45 thereafter permanently connected together, all after the unconnected upper ends of the two sections have been fastened in place on the garment.

LOUIS MARKIN.
